UNITED STATES PATENT OFFICE.

FRITZ ALDENDORFF, OF BERLIN, GERMANY; CHARLOTTE ALDENDORFF, HEIRESS OF SAID FRITZ ALDENDORFF, DECEASED.

AUTOMATIC TELEPHONE SYSTEM.

Original application filed January 12, 1925, Serial No. 1,889, and in Germany, January 14, 1924. Divided and this application filed August 4, 1927. Serial No. 210,698.

This application is a division of patent application Serial No. 1889 of January 12, 1925 and describes an invention which relates to telephone systems operating with selectors and its object is to provide devices by which wrong connections arising from the fact that the line finders, group selectors etc. operate too slowly to respond to very quick movements of the switch controllers, are obviated.

10 A feature of the invention is a registerless, power-driven switching or telephone system in which no revertive impulses sent back from the switches to the switch controlling point are required.

15 The invention is illustrated in the drawing in which

Fig. 1 shows a constructional form of the selector and

20 Fig. 1^a shows a part of a selector whose brush carrier may be moved longitudinally and rotated.

Fig. 1^b shows the longitudinal movement controlling mechanism of the switch of Fig. 1^a.

25 Fig. 2 shows a circuit arrangement for the selector when used as a line finder.

Fig. 3 shows circuits of a selector with longitudinally movable and rotary brush shaft.

30 Fig. 3^a illustrates circuits of a group selector whose brushes execute rotary movements only.

Fig. 4 shows circuits of a connector that executes rotary movements only.

35 Fig. 5 shows a circuit in which the quick stopping effect of the stopping magnet is obtained by inserting a resistance in its energizing circuit.

Fig. 6 shows a circuit in which the quick-stopping effect of the stopping magnet armature is attained by counteracting ampere turns.

40 Fig. 7 illustrates a form of the selector in which, instead of two toothed wheels as in Fig. 1 only one toothed wheel is employed.

Fig. 8 is a diagrammatic representation of one form of contact bank in which the designating contacts are displaced with respect to the conversational contacts.

45 Selectors whose circuits are arranged as shown in Figs. 2, 3^a and 4 may, on the whole, be built in the manner illustrated in Fig. 1 except that a cam disk 300, Fig. 3^a or 400, Fig. 4 which is not provided in Fig. 1, is com-

bined with the brush carrier when the selector 55 is to be used as a group selector or connector.

In Fig. 1, 1 is a shaft which has brushes 2, 3, 4, 5 fixed to it that are insulated from each other and from the shaft. Also fixed on the shaft 1 is a toothed wheel 6 whose hub 7 rests on the bearing 8. Journalled so as to rotate on the shaft 1 is a toothed wheel 10 with a spring box 9. The spring box 9 has an upwardly extending hub 11 and a downwardly extending hub 12 that rests on a bushing 13 65 fixed to the shaft 1. One end of the spring 14 of the spring box is connected to the bushing 13 and its other end is attached to the periphery of the spring box 9. When current impulses are sent through the magnet 15 the 70 spring box 9 is rotated in the direction of the arrow 16, a holding pawl (not shown) being provided which prevents backward rotation of the spring box 9. When the spring box 9 is wound up the wheel 17 is held against 75 movement by the pawl 18 of a magnet 19 so that the shaft 1 with the brushes 2, 3, 4, 5 is also prevented from rotating. Mounted on the wheel 17 are two slip rings 20 to which current is conducted by two brushes 21, 22. 80 The two slip rings are interconnected by a contact that is carried round with the wheel 17 when this wheel is moved out of its normal rotary position with respect to the spring box 9. But as soon as the wheel 10 occupies 85 a certain position with respect to the wheel 17 a pin 24 of the wheel 10 raises a pin 23 and thus opens the contact that interconnects the ring 20. This contact or switch is designated 25 in Fig. 2. The spring 14, when it is wound 90 up, tends to turn the brush carrier 1 with its wheel 17 in the direction of the arrow 26 and it executes a turn in this direction when the starting and stopping magnet 19 is energized.

In a selector with a longitudinally movable 95 shaft 1', Fig. 1^a, a toothed wheel 17' corresponding to the wheel 17, Fig. 1, and a spring box 9' corresponding to the spring box 9, Fig. 1, and having a circle of teeth 10', is provided. The toothed wheel 17' however has 100 a hollow hub 7' upon which the spring box 9' is adapted to rotate. The shaft 1' extends downwardly through the spring box and has a series of circular teeth 27 with which the pawl of a lifting magnet 28 may engage. 105 The shaft 1' has a groove 29 into which a pin 30 arranged in the box of the wheel 17' protrudes, so that the shaft 1' may move length-

wise in the wheel 17' but cannot turn therein. By the lifting magnet 28 the shaft 1' may be lifted step-by-step and when the wheel 17' is then released by a magnet corresponding to 5 magnet 19, Fig. 1, the shaft is rotated by the spring 14' of the spring box until it is stopped in the manner hereinafter described. The shaft 1' is restored to its normal position by its being turned until a pin 31 of the same 10 strikes against a slide way in the form of a long stop 32. When the shaft is in this position a holding pawl 33, Fig. 1^b, will register with a groove 34 in the shaft so that the latter drops down. When the pin 31 has fallen 15 beneath the slide way 32 the spring turns the shaft a little further round until the pin 31 is restored to the position shown in Fig. 1^a and the holding pawl 201, Fig. 3, engages with the wheel 17' and holds it and the brush 20 carrier in the normal position indicated in Fig. 3.

By placing Figs. 2, 3 and 4 side by side a complete circuit arrangement for an exchange with line finders, Fig. 2, group selectors, Fig. 3 and connectors, Fig. 4, is obtained.

It will now be assumed that a subscriber S, Fig. 2, desires to establish a connection with the line 224. When the subscriber S 30 raises his receiver a current flows from the positive pole through the line relay 40, contact 41, substation S, contact 42 of the cut-off relay 43 to the negative pole. The line relay 40 closes its contacts 44, 45 and opens 35 contacts 46, 47. The opening of the contacts 46, 47 results in the positive pole being disconnected from the designating contacts 48, 49. By the closure of the contact 45 the cut-off relay 43 is connected to the test wire 40 50 and test contact 51 of the calling subscriber. At contact 44 a circuit is closed which extends from the positive pole through the starting relay 51 of the line finder 52. The relay 51 sends a current from the positive pole through its contact 53, brush 54 45 of the trunk finder, contact 55 of relay 56, starting magnet 19 to the negative pole. The starting magnet 19 pulls its stopping pawl 57 away from the wheel 17 and this latter is 50 now turned at a high speed by the spring 14, Fig. 1. When the wheel 17 with the brushes 58, 59, 60, 61 is moved out of its normal position the off-normal switch 25 is closed and the relay 56 is energized. The starting magnet 19 is then maintained energized by a current 55 that flows through the contact 62 of the relay 64, wiper 58 and the designating bank contacts 65 that are connected to the positive pole of the battery. The magnet 19 remains 60 energized until the brush 58 reaches the bank contact 49. The armature 57 then retracts and stops the wheel 17 so that the wipers 59, 60, 61 are held on the contacts 66, 67, 68. If magnet 19 does not operate fast enough it 65 could happen that the brush 58 oversteps the

contact 49 and only stops on the next contact 48 from which the positive pole is also disconnected by the contact 47. In any case, if necessary as many contacts 48, 49 are disconnected from the positive pole as are necessary 70 to prevent the brush 58 from flying past the last bank contact that is disconnected from the positive pole, which might happen if the armature 57 acts too slowly. The calling line is always the one that corresponds to the last 75 contact 48 that is disconnected from the positive pole. When the brushes are stopped on the first contact 49 disconnected from the positive pole the magnet 19, as soon as its armature 69 falls back, receives a current 80 impulse that flows through contact 69, 70, 71, 63 to the negative pole. The armature 57 is thus again attracted and allows the toothed wheel 17 to turn through an angle 85 corresponding to a further tooth in the direction of the arrow, because, in consequence of the interruption at 69 and of the disconnection of the positive pole from the contact 48, the armature 57 immediately drops back again and again stops the wheel 17. The test brush 58 will now be resting on the bank contact 51 which is connected through the cut-off relay 43 to the negative pole. Hence the relay 72 will be energized by a current 90 flowing from the positive pole through 53, 54, 72, 59, 51, 45, 43 to the negative pole. The self-interrupter 69 is switched off at 70 so that the armature 57 of the magnet 59 remains still. It is to be noted that the magnet 19 is made to allow its armature 57 to drop 95 back extremely quickly by a condenser 73. The relay 72 closes its contact 73 and thus renders the calling line engaged so that further relays like 72 or test relays in the connectors cannot be energized when the 100 brushes of other selectors are stopped on the bank contacts of the calling line. The line relay 72 by its contacts 74, 75 also connects the calling line through to the group selector, 105 Fig. 3, so that the impulse relay 202 of the group selector is energized. Furthermore the relay 72 by its contact 76 opens the circuit of the rewinding magnet 15 which would otherwise be closed when the release relay 203 and the relay 64 are energized. The 110 calling subscriber now sends in a series of two impulses, i. e. he causes two interruptions of his loop to take place in rapid succession so that the armatures 204, 205 drop back twice and two impulses flow from the negative pole through contact 206 which was closed (due to a current from the negative pole 204, 203, 207 to the positive pole) when the relay 202 was first energized, contact 208, 115 contact 209, lifting magnet 28 to the positive 120 pole. The lifting magnet 28 now raises the shaft 1', Fig. 1^a, with the brushes 210, 211, 212, 213 step-by-step until they reach the second level of the contact bank. The calling subscriber having now sent in his two hun- 125

dred impulses, the armatures 204, 205 now remain attracted for a relatively long interval so that the relay 214 which was energized through 206, 214, 215 is kept short-circuited at contact 216 until its armature drops back and the contact 217 is closed. As the vertical off-normal switch 218 was closed at the first vertical step of the shaft the starting magnet 219 now receives a current which flows from the negative pole through 220, 218, 217, off-normal switch 221, 229 to the positive pole. The wheel 17' and the shaft 1' with the brushes 210-213 is now released for rotary movement so that the spring 14' whirls the brushes round until the magnet 219 which is bridged by a condenser 222 and receives current during rotation of the brushes through the contact 223, brush 213 and bank contacts, such as 224, connected to the negative pole, is deenergized. This deenergization takes place as soon as the brush 213 reaches a contact 224 whose wire 225 is disconnected from the negative pole, this wire leading to a free connector, Fig. 4. The stopping pawl 207 engages with the wheel 17' and arrests the brushes 211, 212, 213 on wires leading to the connector, Fig. 4. In the group selector, Fig. 3, the relay 226 is now energized by a current that flows from the negative pole through 220, retracted armature 227 of the magnet 219, 226, brush 212, wire 228, resistance 401, off-normal contact 402 of the connector to the positive pole. The relay 226 opens the contacts 229, 230, 231 and at the same time extends the voice current wires through the wipers 210, 211 to the impulse relay 402 of the connector. The impulse relay 202 of the group selector is disconnected at contacts 230, 231. This does not however result in the restoration of the group selector because the short circuit around the release relay 203 is kept open at contact 229. The calling subscriber now sends in two tens impulses. On the first retraction of the armature of the impulse relay 402 a current impulse flows from the negative pole through contact 406, 407, 408, wire 409, bank contact 410, wiper 414, contact 415 and through the magnet 419 bridged by the condenser 420. The magnet 419 pulls the holding pawl 418 away from the toothed wheel 417 so that this wheel with the brushes 411-414 is rotated. The brush 414 leaves the contact 410 but is immediately reconnected to negative potential by a long contact 421 so that the magnet 419 remains energized until the brush 410 reaches the contact 422, which in the meantime will have been disconnected from the negative pole by the reenergization of the impulse relay 402. The magnet 419 thus allows the stopping pawl 418 to reengage with the wheel 417 so as to stop the brushes 411, 414 on the set of bank contacts corresponding to the contact 422. When the second tens impulse affects the relay 402 the brushes 411-414 execute a further long step corresponding to their movement from 410 to 422 so that they now reach the contact 423. It is to be noted that the spring which turns the brushes 411-414 is wound in such a way that the long steps of the brushes keep pace with the numerical impulses from the subscriber. During the interval after the series of ten impulses have been sent in the changeover relay 424, which was energized by a current from the negative pole through 406, 422, 425 to the positive pole is deenergized by the short circuit closed at 426 so that the relay 427 is energized by a current that flows from the negative pole through 429, off-normal contact 413, left hand winding of 427 to the positive pole. The impulse wire 431 is connected by the relay 427 and through contact 421 to an interrupter 433 controlled by a cam disk 400, and through this interrupter and a contact 434 it extends to the toothed wheel controlling-magnet 419. When the calling subscriber now sends in his series of unit impulses the magnet 419 is energized at each impulse by a current that flows from the negative pole through 406, 407, 432, 433, 434, 419 to the positive pole. Whenever, during such an impulse, a tooth of the cam disk leaves the interrupter 433, this latter is opened so that the pawl 418 reengages with the toothed wheel 417 and again stops the brushes 411-414 until the next tooth of the cam disk recloses the interrupter 433 and another current impulse flows from the negative pole through 406, 407, 432, etc., and through the magnet 419. Thus, when two unit impulses are sent in the toothed wheel 417 is released twice so that the brushes 411-414 are caused to execute two short steps. The brushes are now set onto the line of No. 222 and the impulse relay 402 is maintained energized so that the change-over relay 424 again lets its armature drop back and thereby connects the negative pole through 429, armature contact 435, to the test relay 436 for the testing operation. It is to be noted here that the relay 437 was energized by the relay 424 after the energization of relay 437. The energizing circuit of the relay 437 extends from the negative pole through 428, 438, 439, right hand winding of relay 437 to the positive pole. By its energization the relay 437 was caused to close the contact 435 and the contact 440 of its locking winding. It will be assumed that the desired subscriber is free. This being the case the test relay 436 is energized so that it closes its contacts 441, 442, 443, 444. At contact 443 a circuit is closed for an intermittent current through the ringing relay 445, this current flowing from the positive pole through the interrupter 446, relay 445, contact 447, contact 443 to the negative pole. At each attraction of the armature of the ringing relay 445 the ringing current generator 448 is connected to

the wanted line through the contacts 441. When the called subscriber responds the relay 449 is energized and the ringing relay 445 is thus disconnected at contact 447. At the same time a back release relay 451 is energized through contact 450, this relay closing a locking circuit for itself at its contact 452. When the called subscriber replaces his receiver the release relay 403 is deenergized by the negative pole being directly connected through 454, 455, to the resistance 456. If the calling subscriber replaces his receiver first the negative pole is directly connected to the resistance 456 through 406 and contact 457. The release relay 403 is thus short-circuited so that it closes its contact 458 and connects the interrupter 459 through 458, 460 of the off-normal switch to the rewinding magnet 415'. At the same time the negative pole is connected through contact 463, off-normal contact 464 to the magnet 419 so that this magnet withdraws the pawl 418 from the wheel 417 and holds it in this position until the off-normal switch 464 is opened by the brushes 411-414 reaching their normal position in which they are shown in the drawing, and the magnet 419 releases the pawl 418 so as to stop the brushes. The off-normal switch 465 keeps the contact 460 closed until the rewinding magnet 415' has completely rewound the spring box of the selector, at which moment the circuit of the rewinding magnet is opened. When the release relay 403 is deenergized it also opens the contact 466 which results in the de-energization of the relay 226 in the group selector, Fig. 3. If the calling subscriber should not have replaced his receiver, the wipers of the group selector will remain on the trunk leading to the connector, Fig. 4. This can be avoided by an auxiliary relay in the group selector. When the calling subscriber hangs up, the impulse relay 202 drops back and the release relay 203 is deenergized so that the circuit of the magnet 219 is closed at contact 250, this circuit standing from the negative pole through 250, off-normal contact 251, 219 to the positive pole the magnet 219 pulls the pawl 201 out of the toothed wheel 17' and the spring 14', Fig. 1^a, now rotates the brushes and the shaft 1' until the pin 31 strikes the guide way 32 and the holding pawl 33, Fig. 1^b, enters the groove 34 of the shaft. The shaft then drops down until the pin 31 leaves the guide way 32. The spring 14' now turns the shaft a little further around until the off-normal contact 251 is opened and the magnet 219 releases the holding pawl 201 and this latter finally arrests the toothed wheel 17'. In the meantime the spring box is rewound by the rewinding magnet 215' which receives current through the interrupter 261, contact 260, 215', contact 262 of the off-normal switch to the positive pole. When the spring box is rewound the off-normal switch is thrown into its normal position and

the circuit of the rewinding magnet 215' is opened at contact 262. By the deenergization of the release relay 203 the restoration of the line finder, Fig. 2, is initiated. When the contact 263 is opened the circuit of the relay 72 is interrupted so that this relay allows its armature to drop back and close the circuit of the restoring magnet 15 at contact 76. The rewinding magnet 15 is energized by a current which flows from the negative pole through the interrupter 80, contact 81, 15, contact 76, contact 83 of the relay 56 to the positive pole or earth. The rewinding magnet 15 now operates until the off-normal contact 51 is interrupted and the relay 56 deenergized. On the deenergization of the relay 56, which only takes place when the spring 14, Fig. 1, is fully rewound the circuit of the rewinding magnet 15 is opened at contact 83. In cases in which a calling subscriber S places his receiver, without the brushes 58, 59, 60, 61 having reached his bank contact set, the relay 64 is energized by a current that flows from the positive pole through 85, 86, 87, left winding of 64 to the negative pole. The relay 64 then closes its contact 81 and thus closes the aforescribed circuit (negative pole, 81, 15, 76, 83, earth) of the rewinding magnet. The rewinding magnet then operates until the spring box is fully rewound. As soon as a line finder is taken into use the trunk finder 52 is caused to place its wipers 87, 54, 86 onto another trunk; for as long as the brush 87 encounters engaged trunks the stepping magnet 87 receives impulses which flow from the negative pole through the interrupter 89, contact 90, magnet 88, brush 87, contact 83 to the positive pole. The brushes of the trunk finder are thus stepped forward until they reach a trunk whose associated contact 83 is open.

In Fig. 7 a manner of arranging the circuits in connection with the designating contacts of the line finder is shown in which the line relay, for example 40' of a calling subscriber also disconnects the battery from the designating contacts 91, 92 as in Fig. 2. The arrangement of Fig. 7 differs from that of Fig. 2 however in that the calling line is connected to the bank contact set of the designating contact 92 that is first reached by the finder wipers and the brushes, if they should overstep the designating contact 92 and only be stopped at the next contact 91, are stopped back by a magnet 93 onto the contact 92.

In the arrangement shown in Fig. 5 the stopping magnet 19' is not bridged by a condenser, but its quick operation is brought about by a resistance 94 being included in its energizing circuit as soon as it has attracted its stopping pawl 57.

In Fig. 6 the stopping magnet 19' has two coils. The retraction of the stopping pawl is brought about by the ampere turns of the energizing winding 95 being counteracted by a

winding 96 at the moment in which the brush 97 reaches a designating contact. The counteracting ampere turns 96 are stronger to a certain degree than the ampere turns 95 but 5 not so strong as to cause the retracted stopping pawl to be attracted again.

In Fig. 3^a a group selector is shown which executes long rotary steps in response to numerical impulses instead of vertical steps. 10 This is accomplished by means of a cam disk 300. The operation of the selector will be obvious from the following description of the operations that take place in setting it onto the desired bank contact group.

15 When a calling party has been connected through to the group selector, Fig. 3^a, its impulse relay 301 is energized. It also results in the energization of the release relay 302 (negative pole, 303, 302, resistance 304, positive pole). Assuming that the calling subscriber sends in two numerical impulses so that the armature of the relay 301 drops back twice, a current impulse will flow at each retraction of the armature from the negative 25 pole through 305, 306, 307, 308, arresting magnet 319, to the positive pole. The magnet 319 pulls the holding pawl 320 away from the toothed wheel 321 and this wheel with the cam disk 300 and the brushes 322, 323, 324, 30 is rotated by the tensioned spring (similar to 14, Fig. 1). As soon as the pawl 320 is disengaged from the tooth of the wheel 321 and this wheel turns through a fraction of the pitch of the teeth the cam disk 300 closes 35 the contact 326, 327 so that the magnet 319 receives a current that flows from the negative pole through 327, 326, 307, 308, 319 to the negative pole. The magnet 319 now remains energized until the spring 326 drops into the 40 next notch 329 of the disk 300 so as to open the contact 327 and cause the pawl 320 to engage with a tooth of the wheel 321. The brushes 322-325 will now have executed one tens step. The next numerical impulse will 45 now reenergize the magnet 319 in a circuit extending from the negative pole through 305, 306, 307, 308, 319 to the positive pole. The stopping pawl 310 is again withdrawn from the toothed wheel 321, the contacts 326, 327 are again closed until the spring 326 50 drops into the notch 329 and the holding pawl 320 again engages the wheel 321 and the brushes will then have completed their second long step.

55 In the interval that ensues after the series of numerical impulses the changeover relay 330 is deenergized by its being short-circuited at contact 331 so that the contact 332 is closed and the relay 333 is energized by a 60 current flowing from the positive pole through 332, 333, off-normal contact 334 to the negative pole. The relay 333 by its contact 334 now connects the magnet 319 to the brush 325. If the brush 325 is now standing 65 on the bank contact of a free trunk the mag-

net 319 remains deenergized and a current flows through the relay 336 in a circuit that extends from the positive pole through 337, 336, 325, wire 338 to the next selector ahead. The relay 336 thus extends the calling party 70 to the next selector. But if the brush 325 is standing on a busy trunk, that is a trunk whose test wire is connected by a contact 339 in the connector to the negative pole, the magnet 319 will be energized by a current flowing 75 from the positive pole through 319, 308, 307, brush 325, contact 339 to the negative pole. The magnet 319 then again withdraws the holding pawl 320 from the wheel 321 and the brushes are rotated by the tension spring until brush 325 reaches a test or designating contact that is not connected with the negative pole and therefore belongs to a free trunk. The holding pawl 320 now drops into the wheel 421 and arrests the brushes on the contact set of the free trunk. 85

When the calling subscriber replaces his receiver the contacts 405, 408 are opened and contacts 340, 341 closed. The magnet 319 is now energized by a current flowing through 90 the off-normal contact 334', 341, 319 to the positive pole and this current continues flowing until the cam disk 300 presses the cam 342 against the spring 344' and thus opens the off-normal contact 334'. The holding pawl 320 is then released by the magnet 319 and the toothed wheel 321 with the cam disk 300 and the brushes is then arrested by the holding pawl 420 in the normal position illustrated. The rewinding magnet 345 receives impulses that flow from the negative pole through the interrupter 346, contact 340, 345, contact 347 until the contact 347 is opened by a cam 348 mounted on the spring box. The spring now being fully rewound 100 the rewinding magnet 345 is deenergized. 105

In Fig. 8 the positions of the bank contacts with respect to each other are diagrammatically illustrated. From the illustration it appears that the designating contacts (as 48, 110 49) are displaced with respect to the other contacts of the contact row so that the voice current contacts 51', 51² and the contacts 51 connected to the holding wire are opposite to gaps between the contacts 48, 49. The holding pawl of the stopping magnet is adjusted so that it arrests the toothed wheel (e. g. 17, Fig. 2) moved with the brushes in a position in which the contacting ends of the wipers stand in a gap between two designating contacts but in the middle of the associated bank contacts 51, 51', 51². By this adjustment the greatest time of deenergization of the stopping magnet is attained. 115

Instead of displacing the bank contacts the same result can of course be obtained by displacing the ends of the brushes with respect to each other in a corresponding manner. 125

In reference to the selector shown in Fig. 1 it is to be mentioned that instead of the 130

groove 29 and the pin 30 a guide fork 40' placed near the periphery of the wheel 17' and a guide arm 41' projecting from the shaft 1' and arranged to slide in the fork 40' may be provided. By this arrangement the play between the shaft 1' and the wheel 17' can easily be reduced to a fraction of a millimetre.

It is also to be noted that the contact 433 10 may simply be opened and closed by the stopping pawl 418 instead of using a special cam disk 400 for this purpose. The cam disk 400 could then be dispensed with.

I claim:—

15 1. An electromechanically controlled telephone system, comprising telephone lines, an impulse producer associated with each line, power driven switches for interconnecting said telephone lines, an arresting wheel 20 on each said switch, an arresting pawl on each switch that cooperates with its arresting wheel, an electromagnet for operating each said pawl to allow the power to move the switch in steps of different lengths, and means 25 for energizing said electromagnets to operate their pawls in response to the impulses produced by said impulse producers.

2. In an electromechanical telephone system, lines, a dial impulse producer in each 30 line, and conversational switches having self-contained power means and brushes adapted to execute steps of different magnitudes in the rhythm of electric impulses produced by said impulse producers.

35 3. In an electromechanical telephone system, line finders and connectors having bank contacts and brushes cooperating therewith, lines connected to said bank contacts, electric impulse producers associated with said lines, 40 stopping magnets for stopping the brushes of said line finders on bank contacts of calling lines, power means for driving line finder brushes in a continuous motion until they are stopped by a stopping magnet, stopping 45 magnets for said connectors that stop the connector brushes at desired points of their contact banks, and power means for moving the connector brushes in steps of different lengths under the control of their stopping 50 magnets and in the rhythm of impulses sent from said impulse producers.

4. In an electromechanical telephone system, line finders and connectors having bank contacts and brushes cooperating therewith, 55 lines connected to said bank contacts, electric impulse producers associated with said lines, stopping magnets for stopping the brushes of said line finders, on bank contacts of calling lines, springs for driving line finder brushes in a continuous motion until they are stopped by a stopping magnet, stopping magnets 60 for said connectors that stop the connector brushes at desired points of their contact banks, and springs for moving the connector brushes in steps of different lengths under 65

the control of their stopping magnets and in the rhythm of impulses sent from said impulse producers.

5. A telephone system comprising calling and wanted lines, line finders and connectors 70 having bank contacts and brushes that cooperate with said bank contacts, springs for moving the brushes of a line finder in a continuous motion into connection with calling lines, and an electromagnet for stopping the 75 line finder on the calling line.

6. A telephone system comprising calling and wanted lines, line finders, group selectors and connectors for interconnecting calling and wanted lines, said selectors and connectors having self-contained power means, selecting impulse producers associated with said lines, and electromagnets for controlling the movements of said selectors and connectors in steps of different lengths in the 80 85 rhythm of impulses sent from said impulse producers.

7. A telephone system comprising calling and wanted lines, switches having spring driven wipers adapted to execute separate 90 long and short steps for interconnecting calling and wanted lines, and electromagnets for determining the lengths of steps executed by said switches in their line-interconnecting operations.

8. A telephone system comprising calling and wanted lines, switches having spring driven wipers adapted to execute separate long and short steps for interconnecting calling and wanted lines, electromagnets for determining the lengths of steps executed by 100 said switches in their line-interconnecting operations, and electric condensers for quickening the action of the armatures of said electromagnets.

9. A telephone system comprising calling and wanted lines; trunks; line finders, group selectors and connectors; a spring motor for moving a line finder in one continuous motion onto a calling line, a spring motor for moving a group selector stepwise onto a desired group and then in one continuous motion onto a said trunk, and a spring motor for moving a connector stepwise first onto a desired group and then onto the wanted line in the group; and electromagnets for determining the extents of the switch movements caused by said springs.

10. A telephone system comprising calling and wanted lines; trunks; line finders, group selectors and connectors; a spring motor for moving a line finder in one continuous motion onto a calling line, a spring motor for moving a group selector stepwise onto a desired group and then in one continuous motion onto a said trunk, and a spring motor for moving a connector stepwise first onto a desired group and then onto the wanted line in the group; electromagnets having armatures for determining the extents of the switch movements caused by said springs, and condensers for 110 115 120 125 130

quicken the action of the armatures of said electromagnets.

11. A telephone system comprising calling and wanted lines, power driven line finders and connectors for interconnecting calling and wanted lines, a brush carrier and toothed wheel in each line finder and connector, an armature normally in engagement with each toothed wheel, and electromagnets for raising said armatures from said toothed wheels to allow the brushes of the line finders and connectors to move onto calling and wanted lines.

12. A telephone system comprising calling and wanted lines, spring driven line finders and connectors for interconnecting calling and wanted lines, a brush carrier and toothed wheel in each line finder and connector, an armature normally in engagement with each toothed wheel, and electromagnets for raising said armatures from said toothed wheels to allow the brushes of the line finders and connectors to move onto calling and wanted lines under control of the associated springs.

13. A telephone system comprising calling and wanted lines; trunks; power driven line finders, group selectors and connectors for interconnecting calling and wanted lines; a brush carrier and toothed wheel in each line finder, group selector and connector; an armature normally in engagement with each toothed wheel; and electromagnets for raising said armatures from said toothed wheels to allow the brushes of the line finders, group selectors and connectors to move onto calling lines, trunks and wanted lines respectively.

14. A telephone system comprising calling and wanted lines; trunks; spring driven line finders, group selectors and connectors for interconnecting calling and wanted lines; a brush carrier and toothed wheel in each line finder, group selector and connector; an armature normally in engagement with each toothed wheel; and electromagnets for raising said armatures from said toothed wheels to allow the brushes of the line finders, group selectors and connectors to move onto calling lines, trunks and wanted lines respectively.

15. A telephone system comprising calling and wanted lines, power driven line finders and connectors for interconnecting calling and wanted lines, a brush carrier and toothed wheel in each line finder and connector, an armature normally in engagement with each toothed wheel, electromagnets for raising said armatures from said toothed wheels to allow the brushes of the line finders and connectors to move onto calling and wanted lines, and condensers for quickening the dropping movements of said raised armatures.

16. A telephone system comprising calling and wanted lines; trunks; power driven line finders, group selectors and connectors for interconnecting calling and wanted lines; a brush carrier and toothed wheel in each line

finder, group selector and connector; an armature normally in engagement with each toothed wheel; electromagnets for raising said armatures from said toothed wheels to allow the brushes of the line finders, group selectors and connectors to move onto calling lines, trunks and wanted lines respectively, and condensers for quickening the dropping movements of said raised armatures.

17. A telephone system comprising calling and wanted lines; impulse producers; power driven line finders and connectors for interconnecting calling and wanted lines; a brush carrier and toothed wheel in each line finder and connector; an armature normally in engagement with each toothed wheel in each line finder and connector; electromagnets in the line finders for raising the armatures from their toothed wheels to permit the brushes to move onto calling lines; and electromagnets for raising from and lowering onto the toothed wheels of the connectors the armatures of the connectors in the rhythm of the impulses sent from said impulse producers.

18. A telephone system comprising calling and wanted lines; impulse producers; spring driven line finders and connectors for interconnecting calling and wanted lines; a brush carrier and toothed wheel in each line finder and connector; an armature normally in engagement with each toothed wheel in each line finder and connector; electromagnets in the line finders for raising the armatures from their toothed wheels to permit the brushes to move onto calling lines; and electromagnets for raising from and lowering onto the toothed wheels of the connectors the armatures of the connectors in the rhythm of the impulses sent from said impulse producers.

19. A telephone system comprising calling and wanted lines; trunks; impulse producers; power driven line finders, group selectors and connectors for interconnecting calling and wanted lines; a brush carrier and toothed wheel in each line finder and group selector; an armature adapted to engage with each toothed wheel in each line finder and group selector; electromagnets in the line finders for moving the armatures relatively to their toothed wheels to permit their brushes to move onto calling lines; and electromagnets in the group selectors for moving the armatures relatively to their toothed wheels to permit their brushes to move onto free trunks.

20. A telephone system comprising calling and wanted lines; trunks; impulse producers; spring driven line finders, group selectors and connectors for interconnecting calling and wanted lines; a brush carrier and toothed wheel in each line finder and group selector; an armature adapted to engage with each toothed wheel in each line finder and group selector; electromagnets in the line finders for moving the armatures relatively to their toothed wheels to permit the brushes to move

onto calling lines; and electromagnets in the group selectors for moving the armatures relatively to their toothed wheels to permit their brushes to move onto free trunks.

- 5 21. In a line connecting system, two-wire lines, an impulse producer associated with each line, line relays, a switch comprising bank contacts, a brush carrier, brushes that wipe over said bank contacts, a self-contained power device for driving said brushes in a continuous motion over any plurality of said bank contacts, a toothed arresting member on said brush carrier, a starting and stopping member adapted to cooperate with said toothed member for starting and stopping said brushes, an electromagnet for controlling said starting and stopping member, an electric circuit for energizing said electromagnet, means controlled by current impulses 10 from said impulse producer through a said line and a line relay for closing said circuit to energize said electromagnet and start the continuous motion of said brushes, and means whereby said electromagnet is deenergized 15 to cause said member to stop the brushes on any desired individual bank contact.

22. In a line connecting system, two-wire lines, an impulse producer associated with each line, line relays, a switch comprising bank contacts, a brush carrier, brushes that wipe over said bank contacts, a spring for driving said brushes in a continuous motion over any plurality of said bank contacts, a toothed arresting member on said brush carrier, a starting and stopping member adapted to cooperate with said toothed member for starting and stopping said brushes, an electromagnet for controlling said starting and stopping member, an electric circuit for energizing said electromagnet, means controlled by current impulses 20 from said impulse producer through a said line and a line relay for closing said circuit to energize said electromagnet and start the continuous motion of said brushes, and means whereby said electromagnet is deenergized 25 to cause said member to stop the brushes on any desired individual bank contact.

23. In a line connecting system, two-wire lines, an impulse producer associated with said line, line relays, a switch comprising bank contacts, a brush carrier, brushes that wipe over said bank contacts, a spring for driving said brushes in a continuous motion over any 30 plurality of said bank contacts, a toothed arresting member on said brush carriers, a starting and stopping member adapted to cooperate with said toothed member for starting and stopping said brushes, an electromagnet for controlling said starting and stopping member, an electric circuit for energizing said electromagnet, means controlled by current impulses 35 from said impulse producer through a said line and a line relay for closing said circuit to energize said electromagnet and start the continuous motion of said brushes, and means whereby said electromagnet is deenergized 40 to cause said member to stop the brushes on any desired individual bank contact.

24. In a line connecting system, two-wire lines, an impulse producer associated with said line, line relays, a switch comprising bank contacts, a brush carrier, brushes that wipe over said bank contacts, a spring for driving said brushes in a continuous motion over any 45 plurality of said bank contacts, a toothed arresting member on said brush carriers, a starting and stopping member adapted to cooperate with said toothed member for starting and stopping said brushes, an electromagnet for

controlling said starting and stopping member, an electric circuit for energizing said electromagnet, means controlled by current impulses from said impulse producer through a said line and a line relay for closing said circuit to energize said electromagnet and start the continuous motion of said brushes, means whereby said electromagnet is deenergized to cause said member to stop the brushes on any desired individual bank contact, and means for retensioning said spring 50 after each use of same.

25. In a high-speed telephone system, calling lines, called lines, trunk lines leading from said calling lines toward said calling lines, a plurality of bank contacts in which said trunk lines terminate, a circuit controlling brush adapted to wipe over said contacts, a shaft to which said brush is attached, a toothed wheel for said shaft, a stopping pawl for said wheel, a magnet for controlling said pawl, means controlled by a calling line for energizing said magnet to allow said brush to be moved, means for designating one of said bank contacts, means responsive to the movement of said brush from a non-designated preceding contact to a succeeding designated contact, for causing said magnet to be deenergized, means responsive to the deenergization of said magnet for causing said pawl to rapidly engage said toothed wheel, and a condenser 85 for accelerating the deenergization of said magnet.

26. In a high-speed telephone system according to claim 24 in which the accelerating condenser is connected in parallel with the 90 controlling magnet.

27. In a telephone system, a plurality of telephone lines, a plurality of bank contacts in which said lines terminate, a set of spring driven brushes, a toothed wheel and cooperating detent for positively arresting said brushes when they reach a designated set of contacts, and circuit arrangements controlled over said lines for causing said switch to act as a telephone line selector.

28. In a telephone system, a plurality of telephone lines, a plurality of bank contacts in which said lines terminate, a set of spring driven brushes, a toothed wheel and cooperating detent for positively arresting said brushes when they reach a designated set of contacts, and circuit arrangements controlled over said lines for causing said switch to act as a group selector.

In testimony whereof I have affixed my signature.

FRITZ ALDENDORFF.
